UNITED STATES PATENT OFFICE.

JOHN P. RICHTER, OF NEW YORK, N. Y.

ORNAMENTAL GLASS.

1,241,767.

Specification of Letters Patent. Patented Oct. 2, 1917.

Application filed June 30, 1916. Serial No. 106,774.

To all whom it may concern:

Be it known that I, JOHN PAUL RICHTER, a citizen of the United States, and resident of the city of New York, Jamaica Estates, 5 borough of Queens, in the county of Queens and State of New York, have invented certain new and useful Improvements in Ornamental Glass, of which the following is a specification.

10 This invention relates to certain improvements in the manufacture of ornamental glass and more particularly to that type in which the parts, units or structure presenting or forming the ornamental pattern 15 are embodied or contained within the sheet or pane of glass or other vitreous substance.

The common type of wire glass, in which a netting or metallic trellis is embodied in the glass to act primarily as a reinforcement, 20 has proven satisfactory for use as window panes in various places where an ornamental appearance is not particularly desired or, at least, is not important. So far as I am advised, the attempts which 25 have heretofore been made to render the sheets or panes sufficiently ornamental and attractive in appearance to secure their extensive use in banks, offices and other places where an attractive appearance, in addition 30 to the well known useful properties, is desired, have not met with complete success, due either to the difficulties encountered in the manufacture or to the defects in the completed structure, resulting in a loss of 35 the desirable strength, homogeneity or other property.

The main object of my invention is to so construct, connect and combine the units or parts going to make up the ornamental pattern 40 that the same may be incorporated in the glass in the same way that it is now employed for incorporating ordinary wire mesh, and when incorporated will be properly positioned at a substantially uniform 45 distance from the surface of the glass and will not act to increase the fragility or in any way prevent the use of the product for any purpose for which ordinary wire glass is now used.

50 In its preferred embodiment, my improved construction includes a wire mesh of such weave and size of wire that it may be combined with the glass or other vitreous

material at the time of and while it is being formed into a sheet or plate so that the 55 interstices in the pattern permit the glass to flow or fuse therethrough to form an integral mass.

The wire mesh serves as a ground-work or support for the elements or parts going 60 to make up the design. These elements may be small objects, preferably in the form of plates, sheets or disks, and cut, stamped, or otherwise formed of any desired contour. The desired number of these objects may 65 be secured to the wire mesh so as to form letters, numerals, symbolic designs, or arranged in accordance with any predetermined pattern. They may be secured to the wire mesh in any suitable manner, preferably 70 by means which will not be affected by the temperature of the molten glass. The wire mesh may be of the ordinary form with hexagonal apertures, or may be of any other desired form suitable for supporting and 75 properly positioning the elements of the pattern. The wires themselves or certain particular wires may be rendered conspicuous 80 by their larger size or by a coating so as to form a part of the design itself, or the wires may be made so small as to be inconspicuous to the casual observer. In fact, the wires may serve solely as the means for supporting, introducing and positioning the 85 elements of the design within the glass and may largely, if not entirely, lose their reinforcing function.

Reference is to be had to the accompanying drawings, in which I have illustrated certain embodiments of my invention, but I 90 desire it to be understood that I am not to be limited to the specific constructions shown in said drawings, as various other forms and arrangements may be readily designed within the scope of my invention. In these 95 drawings—

Figure 1 is a face view of a panel having the pane constructed in accordance with my invention.

Fig. 2 is an enlarged sectional view on 100 the line 2—2 of Fig. 1,

Fig. 3 is a face view of one unit showing a modified form of connecting or securing means,

Fig. 4 is a transverse section upon the 105 line 4—4 of Fig. 3,

Fig. 5 is a face view of a different arrangement of wire mesh and two different forms of design units secured, and

5 Figs. 6 and 7 are face views of further forms of design units.

In the specific construction illustrated in Figs. 1 and 2, I employ a wire mesh 10 formed of a series of wires, all extending in the same general direction. Each wire has 10 portions twisted together with portions of the adjacent wires so as to form hexagonal apertures. The wire may be of any suitable material and may be finished either dull or polished, depending upon the conspicuously desired. It may also be of 15 finer or greater size, depending upon the thickness of the glass and also the desired strength and conspicuously. Upon this wire mesh is arranged a series of units or 20 elements going to make up the body of the design. These are shown as small metal plates 12, each in the form of a Greek cross and each with its upper and lower extremities 13 bent over to lie parallel with the body portion and to grip the wire and hold the 25 plate in position. The plates are shown as being superposed upon certain of the twisted portions of the wire but it is of course evident that they may be secured to any other 30 portion of the wire mesh.

In Figs. 3 and 4, I have shown a somewhat similar plate 13 which is secured in place to the wire mesh 10 by two small lugs or projections 14 struck out from the body 35 portion of the plate adjacent to the center and bent to partially encircle or grip the wires in the rear of the body of the plate.

As previously indicated, the plates may 40 be of any desired material which will not be affected by the temperature of molten glass. I find that by using dull wires of some suitable white metal and bright or polished copper plates, a very effective design may be produced.

45 The form of the wire mesh is not essential unless a particular form be desired for producing some particular design. In Fig. 5 I have shown a wire mesh which includes wires 15 arranged substantially at right angles to a second set of wires 16 so as to leave rectangular apertures. The wires may 50 be irregularly spaced or may be arranged in pairs so as to produce apertures in the form of large squares, small squares and 55 rectangles. Different objects or elements going to make up the design may be secured to this wire mesh, depending upon the size and shape of the aperture over which the object is to be secured or depending upon 60 the design or effect to be produced.

The wires may be interwoven so as to form a complete substantially permanent structure, irrespective of the elements of the design, or the two sets of wires may be merely 65 superposed and they may be held together

at the overlapping points by elements of the design. In Fig. 4 I have shown one plate 17 in the form of an open frame with inwardly curved sides and superposed on one of the large square apertures of the wire 70 mesh. Each corner of this frame may be bent over the adjacent wire to hold the part in position. Over the small squares I have shown narrow strips 18 at right angles to each other and overlapping certain of the 75 wires and secured in place in any suitable manner as for instance by bending the ends of the strips around into engagement with the opposite sides of the wire.

In Fig. 6, I have shown a plate 19 substantially in the form of a ring with projecting lugs 20 which may be left as shown or which may serve as attaching lugs and be bent around the wire.

In Fig. 7, I have shown a plate 21 in the 85 form of a crescent with similar lugs 20.

A design may be made up entirely of similar units as in Fig. 1 or may be made up of a plurality of different kinds of units as in Fig. 5, or the units themselves may be 90 in the form of small letters, numerals, or other devices to form a legend, title, or otherwise impart information irrespective of any attempt to secure a particularly ornamental effect.

Having thus described my invention, what I claim as new and desire to secure by Letters Patent is:

1. A glass plate having wires embedded therein and a plurality of units of definite 100 substantially identical form secured to said wires and coöperating with said wires to form a design.

2. A glass plate having wires entirely embedded within the body of the glass and 105 a plurality of units forming a design and also entirely embedded within the glass, said units being of definite form and large in respect to the diameter of the wires and spaced and positioned in respect to each 110 other by said wires.

3. A glass plate having wire mesh entirely embedded within the body of the glass and a plurality of units forming a design and also entirely embedded within the glass, 115 said units being of a size bearing a predetermined relationship to the size of the mesh and being rigidly secured to said wires prior to the introduction of said wires and units into the glass.

4. A glass plate having a wire mesh embedded therein, and a plurality of small thin plates of non-combustible material secured to said wire mesh and also embedded within the glass and each of a width materially 125 greater than the diameter of the wires of the mesh.

5. An article of manufacture including a wire mesh, a plurality of elements secured thereto at spaced points and arranged to co- 130

operate with the wires of the mesh to form a design, and a sheet of glass inclosing said wires and units.

6. An article of manufacture including a plurality of wires, a series of small metal plates each having a portion thereof bent around an adjacent wire portion to space and position said plates in respect to each other, and a sheet of glass reinforced by

10 said wires.

7. An article of manufacture including a plurality of wires, a series of small metal plates each having a portion thereof bent around an adjacent wire portion to space

15 and position said plates in respect to each

other, and a sheet of glass covering said wires.

8. The method herein described for making ornamental glass sheets which consists in securing a plurality of small metal plates 20 to a wire mesh and spaced and positioned in respect to each other in accordance with a predetermined pattern and entirely embedding said wire mesh and plates within a sheet of glass.

Signed at New York city, in the county of New York and State of New York this 28th day of June, A. D. 1916.

JOHN P. RICHTER.
